(57) **CLAIM**

The ornamental design for an electric scooter, as shown and described.

DESCRIPTION

FIG. 1 is a top, front and right side perspective view of an electric scooter showing our new design;
FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1;

FIG. 11 is an enlarged view of portion 11 in FIG. 1;

FIG. 12 is an enlarged view of portion 12 in FIG. 1;

FIG. 13 is an enlarged view of portion 13 in FIG. 1;

FIG. 14 is an enlarged view of portion 14 in FIG. 2;

FIG. 15 is an enlarged view of portion 15 in FIG. 2; and,

FIG. 16 is an enlarged view of portion 16 in FIG. 2.

The dash-dot broken lines in FIGS. 1, 2 and 9-16 are included to show enlarged partial views. All other broken lines represent portions of the electric scooter that form no part of the claimed design. None of the broken lines form a part of the claim.

The oblique shade lines in the drawings represent reflective surfaces.
